UNITED STATES PATENT OFFICE.

SADIE E. KALFUS, OF BERKELEY, CALIFORNIA.

REVERSIBLE CUFF.

1,259,872.

Specification of Letters Patent. Patented Mar. 19, 1918.

Application filed October 13, 1917. Serial No. 196,486.

To all whom it may concern:

Be it known that I, SADIE E. KALFUS, a citizen of the United States, and a resident of Berkeley, county of Alameda, and State 5 of California, have invented a certain new and useful Reversible Cuff, of which the following is a specification.

The invention relates to reversible cuffs and particularly to soft fold cuffs, usually 10 known as French cuffs.

An object of the invention is to provide a soft fold cuff which may be turned to present a clean surface when the exposed surface becomes soiled.

Another object of the invention is to provide a reversible cuff having three wearing 15 surfaces.

The invention possesses other advantageous features, which, with the foregoing, 20 will be set forth at length in the following description where I shall outline in full, that form of cuff of my invention which I have selected for illustration in the drawings accompanying and forming part of the 25 present specification.

Referring to said drawings:

Figure 1 is a perspective view of the cuff of my invention in extended position, a part thereof being broken away to disclose the 30 construction.

Fig. 2 is a perspective view of the cuff in its first position.

Fig. 3 is a perspective view of the cuff in its second position.

Fig. 4 is a perspective view of the cuff in its third position.

The cuff of my invention is composed of three members, each of which, at different times, serves as the wearing surface. The 40 members are soft and pliable so that they may be readily folded over to present the desired wearing surface. The member 2, which constitutes the wrist band, is preferably provided with a lining 3 interposed 45 between the inner and outer faces 4 and 5. The lining is stitched to the material of the inner face by the lines of edge stitching 6 and the line of cross stitching 7. The line of stitching 7 lies below the line of fold 50 of the cuff and extends only through the lining and the material of the inner face, so that the stitching is not visible at the fold or at the outside surface 5 of the band. The lines of edge stitching 6 terminate a 55 short distance from the line of fold, for reasons that will be hereinafter apparent.

The material forming the inner surface 4 of the band extends beyond the fold a distance, preferably somewhat less than the width of the band, and the material forming the outer surface 5 is similarly extended. The extension 8 of the inner piece is then folded back on the line of the fold and a piece of material of the same size as the two extended pieces is laid over and stitched 60 to the extended pieces by the edge stitching 12, the stitching terminating a short distance from the line of fold, so that the band will not be sewn to the extended portions. These extended portions form the fold cuffs 65 14-15 and may be folded to lie on either side of the wrist band. The cuff 14 is provided adjacent the opposite edges with button holes 16 for the reception of a cuff-button and the cuff 15 and band 2 are similarly provided with button holes 17-18, 70 the button-holes 16-17-18 on both sides of the cuffs and bands being equally spaced from the line of fold, so that when the cuff is folded and the edges brought together, 75 the six button-holes will register. The band 2 is preferably made wider than either of the cuffs 14-15, so that when the cuff is laid out for ironing, the seam between the band and the shirt sleeve 19 will not underlie and 80 produce a ridge on the fold cuff members. 85

The cuff presents three wearing surfaces, and may be readily folded to present any desired surface. When first worn, both cuff members 14 and 15 are folded to overlie the 90 band, as shown in Fig. 2, cuff 14 then presenting the wearing surface. When this surface becomes soiled, the cuff member 14 is folded to lie within the band as shown in Fig. 3, and cuff 15 presents the wearing 95 surface. When this becomes soiled, the cuff member 15 is folded to lie within the band as shown in Fig. 4, and the outer surface 5 of the band 2 then becomes the wearing surface. The button-holes register in all positions of the cuff members and the cuff offers a presentable appearance at all times. The two layers of fabric which form the cuff members 14 and 15 are sewed together only at the edges so that no stitching occurs along 100 the fold nor adjacent the fold on any of the wearing surfaces. 105

I claim:

1. The combination with a shirt sleeve, of a wrist band permanently attached thereto, two flexible cuff members extending from the outer end of said wrist band, each of 110

which members is adapted to be turned either inside or outside of the wrist band, said wrist band and cuff members each being provided with button-holes positioned 5 to register when both cuff members are folded back on the wrist band.

2. The combination with a shirt sleeve, of a wrist band including an inner and an outer layer of fabric permanently attached 10 thereto, integral extensions of said layers projecting beyond the end of said band, a layer of fabric overlying said extensions and stitched thereto at the edges only, forming two separate flexible cuff members each, 15 of which is adapted to be folded inwardly or outwardly on the wrist band, a button-hole adjacent each edge of each cuff member at the same distance from the end of the wrist band, and a button-hole adjacent each edge 20 of the wrist band at the same distance from the end of the band as the button-holes in the cuff members.

3. The combination with a shirt sleeve of

a wrist band composed of an inner and outer fabric and an interposed lining, a line 25 of stitching securing the inner fabric only to the lining adjacent the outer end of the wrist band, integral extensions of said layers projecting beyond the outer edge of the band, a layer of fabric overlying said extensions and secured thereto at the edges only by stitching, forming two separate flexible cuff members adapted to be folded back on either or both sides of the wrist band, the lines of stitching being arranged 30 so that the stitching does not occur on the outside of the cuff adjacent the fold in any position of the cuff members and button holes in said cuff members and wrist band.

In testimony whereof, I have hereunto set 40 my hand at San Francisco, California, this 8th day of October, 1917.

SADIE E. KALFUS.

In presence of—
H. G. PROST.
